David Koch, Highland Park, Ill., assignor to
Morris Kurtzon, Inc., Chicago, Ill., a corpora-
tion of Illinois

Application June 1, 1951, Serial No. 15,373

Term of patent 7 years

(Cl. D10—8)

To all whom it may concern:

Be it known that I, David Koch, a citizen of the United States, and resident of Highland Park, in the county of Lake and State of Illinois, have invented a new, original, and ornamental Design for a Drawer Pull, of which the following is a specification, reference being had to the accompanying drawing, forming a part thereof.

Fig. 1 is a top perspective view of a drawer pull, showing my new design.

Fig. 2 is an end elevational view thereof.

Fig. 3 is a bottom perspective view thereof.

I claim:

The ornamental design for a drawer pull, substantially as shown.

DAVID KOCH.
